UNITED STATES PATENT OFFICE.

RUDOLF JAY, OF LEIPSIC, GERMANY.

ENGRAVING-MACHINE.

SPECIFICATION forming part of Letters Patent No. 704,193, dated July 8, 1902.

Application filed October 9, 1901. Serial No. 78,053. (No model.)

To all whom it may concern:

Be it known that I, RUDOLF JAY, a citizen of Germany, and a resident of Leipsic, Germany, have invented certain new and useful 5 Improvements in Engraving-Machines, of which the following is a specification.

This invention relates to an engraving-machine more particularly designed to reproduce patterns in relief by means of engraving-tools which are gradually conducted over the surface of the work-pieces and to which a rapid rotating motion is imparted.

The invention consists more particularly in the means by which a uniform motion is imparted to the engraving-tools independently from the motion imparted to the work-pieces, so that a more reliable and uniform movement of the engraving-tools is insured.

In the accompanying drawings, Figure 1 is 20 a front elevation of the machine; Fig. 2, an end elevation, and Fig. 3 a plan.

a is an electric motor turning by worm *a'* and the worm-wheel *b'* the main shaft *b*, to which the worms *b²* *b³* *b⁴* are attached. By 25 means of the worm-wheels *c'* *d'* the shafts *c* *d* are uniformly turned. The shaft *c* bears upon its end the pattern-plate *c²*, while the shafts *d* carry the plates *d²* to be engraved.

b⁵ is a pulley fixed to shaft *b*, which is connected by belt *g* with pulley *f'*, fast on shaft *f*. Shaft *f* transmits motion by worm *f²*, worm-wheel *h'*, shaft *h*, worm *h²*, and worm-wheel *i'* to a screw *i*. In this way results a 35 downward motion of a slide *k*, engaged by said screw. To the slide *k* is pivoted a lever *m*, carrying the tracing and engraving tools *o* *q* and connected by universal joint *n'* *n²* to an arm *n* of the machine-frame *A*.

40 Upon the lever *m* is mounted the holder *o'* for the tracing-tool and two, more or less, sliding holders *q³* of the engraving-tools *q*. The spindles *q'* of the engraving-tools *q* turn in bearings *q²* of the sliding tool-holders *q³* and 45 are each driven by an electric motor *s*, mounted upon the spindle *q'*. These motors are thus also carried by the tool-holders *q³* and cause the engraving-tools to rotate with uniform speed and entirely independent from the 50 main shaft *b*. In this way all transmission is avoided and a quiet and uniform movement of the engraving-tools is insured.

The slide *k* has a contact *t*, gliding over a

number of contacts *u* of an electric resistance. This resistance is switched into the 55 circuit of the electric motor *a* in such a manner that by moving the slide *k* with the contact *t* downward the speed of the shaft *b* is gradually diminished. Thus as the path of the tools *o* and *q* is increased the movement 60 of the model and work-pieces is correspondingly decreased.

The operation is as follows: The tools *o* and *q* are set in proper relative position to the pattern and work-pieces, and the electric 65 motors *a* and *s* are switched in. The motor *a* will by shaft *b* rotate the pattern *c²* and the work-pieces *d²*. The shaft *b* will also by the transmission described turn the screw *i* to gradually lower the slide *k*, and thereby de- 70 press the end of lever *m*, so as to cause the pattern and work-pieces to be gradually traversed by the tools. After the operation is completed the motors *a* and *s* are switched off and the slide *k* is raised to its elevated position by means of a suitable hand-crank *u'*, 75 ready for the next operation.

What I claim is—

1. In an engraving-machine, the combination of a rotatable screw with a slide engaged 80 thereby, a lever pivoted to the slide, a tracing-tool and an engraving-tool mounted upon the lever, an electric motor for driving the screw, a resistance in the circuit of the motor, and a contact mounted upon the slide 85 and gliding upon said resistance, substantially as specified.

2. In an engraving-machine, the combination of an electric motor with a shaft driven thereby, pattern-plates and work-plates rotated by said shaft, a screw, means intermediate the shaft and screw for rotating the latter, a slide engaged by the screw, a lever pivoted to the slide, a tracing-tool and an engraving-tool carried by the lever, means for 90 rotating the engraving-tool, an electric resistance in the circuit of the electric motor, and a contact on the slide that engages said resistance, substantially as specified.

Signed by me at Leipsic, Germany, this 24th 100 day of September, 1901.

RUDOLF JAY.
